PULSED RADIO REMOTE-CONTROL SYSTEM

Emile Labin, New York, N. Y., assignor to Federal Telephone and Radio Corporation, New York, N. Y., a corporation of Delaware

Application April 18, 1945, Serial No. 588,961

6 Claims. (Cl. 343—225)

1

The present invention relates to remote control systems and particularly to a radio remote control system for the selective control of a plurality of separate utilization devices.

For certain uses, particularly military, it is desirable to have a remote control radio system which is not easily detected and which cannot be readily jammed or affected by noises. Furthermore if such systems are to be used for the control of moving craft or vehicles, as for example the control of a pilotless glider from a mother plane, it is desirable that the control equipment be relatively simple in construction and operation, positive in action, and capable of operating on rather small power systems.

An object of the present invention is the provision of a remote control radio system which will meet the foregoing requirements.

In carrying out my invention, control is effected by energy of a given carrier frequency in the form of pulses of preferably several hundred microseconds duration. The use of pulses permits obtaining relatively large amounts of power for short periods of time from relatively small power equipment. Furthermore, since, according to my invention, these pulses are transmitted only when changes are to be made in the operation of the control device, as for example changes in the direction of the pilotless glider, these pulses are not readily detected. Since these pulses are not continuously transmitted in order for them to be detected, the receiver must be tuned to the proper wavelength at the proper time.

To effect different controls such as up and down, right and left, required in controlling the movements of the glider, for example, the carrier frequency of the transmitted pulses (from the controlling plane) is modulated by a selected one of a number of sub-carrier frequencies. In the receiver (in the pilotless glider) the pulses are separated according to the sub-carrier frequency with which they are modulated and sent along a given channel to actuate a utilization device which produces the desired operation (change in direction of the glider).

Other and further objects of the present invention will become apparent and my invention will be best understood from the following description of an embodiment thereof, reference being had to the drawing, in which:

Figure 1 is a block diagram of a remote control system embodying my invention; and

Figure 2 is a plan view of the control box 4 with the cover removed.

2

Since the particular embodiment of my invention illustrated in the Fig. 1 is adapted to control the flight of a glider from a mother plane, it will be described in connection therewith.

5 The system consists of a transmitter 1 which is mounted in the plane and a receiver 2 which is mounted in the glider. Flight of the glider is controlled from the plane by moving an arm 3 in a control box 4 to various positions designated, such as for example left, right, up, down and reset to actuate relays 5—9 in the receiver which relays control the flight of the glider by controlling the rudder, elevators, ailerons, etc. The control box 4 is provided with switches or relays arranged so that when the arm 3 is moved into any of the operative positions (left, right, up, down and reset) two operations occur.

The first of these operations is the actuation of the pulse generator 19, the pulse output of 20 which is passed through an amplifier 11 and then used to key a sub-carrier frequency oscillator 12. The pulses keying oscillator 12 are preferably relatively long such as for example of the order of 200 microseconds.

25 The second of the operations is to select a sub-carrier frequency. Oscillator 12 operates at one of the five sub-carrier frequencies, preferably spaced over a band width of the order of one megacycle, the five frequencies ranging for example from one to two or two to three megacycles or the like. The particular frequency at which oscillator 12 operates for a given pulse or train of pulses is determined by the operative position to which arm 3 of control box 4 is moved.

30 For this purpose control box 4 is connected by lines 13—17, one line for each operative position of arm 3, to oscillator 12 and through these lines the control box 4 controls or determines the particular frequency at which oscillator 12 operates. This may be accomplished by any well-known means such as for example by connecting said lines inside the oscillator to electronic switches which switch different tank coils into the oscillator plate circuit.

35 40 45 The output of oscillator 12 is in the form of pulses carrying the selected one of the sub-carrier frequency oscillations. This energy is used to modulate a carrier frequency oscillator 18, as for example by plate modulation. The carrier frequency oscillator 18 is also keyed by the pulses from amplifier 11 as indicated by line 19. The oscillator 18 operates at a carrier frequency preferably of the order of several hundred megacycles. It will be seen that the output of the oscillator 18 consists of a pulse of car-

rier frequency modulated with the selected sub-carrier frequency. The output of oscillator 18 is next fed to a broad band antenna system 20 and thereby radiated.

The receiver 2 in the glider picks up this energy on its antenna system 21, the pulse then being fed through a broad band radio frequency amplifier 22 tuned to the carrier frequency, to a detector 23 in which the carrier frequency is removed. The output of detector 23 is fed through a high pass filter 24, which reduces the effects of harmonics in the sub-carrier frequencies, to an amplifier 25 preferably of the type known as "video amplifiers" and giving a relatively flat response over the entire sub-carrier frequency band width.

The output of amplifier 25 is connected to five separate channels designated generally by the numerals 26-30. Since all of these channels are similar in construction, only channel 26 will be described. The output of amplifier 25 is connected to a selector filter 31 in channel 26 which is designed to pass one of the five sub-carrier frequencies. The other channels have similar selector filters, each of which passes a different one of the five sub-carrier frequencies. The output of filter 31 is fed to a limiter 32 of the threshold clipping type. This limiter serves to prevent pulses of less than a given amplitude from controlling the operation of the glider. This also serves to prevent interference with said operation by noise or jamming. The output of limiter 32 is then fed through an integrator 33 in which the train of pulses is integrated and thence to a sensitive relay 5, which relay 5 controls one of the movements of the glider in flight, as for example either up, down, right, left or reset. Likewise each of relays 6, 7, 8 and 9 connected in channels 27-29 respectively controls a different movement of the glider.

While numerous control boxes suitable for controlling the transmitter, as indicated hereinabove, may be employed and would readily occur to those versed in the art, a simple one for this purpose is illustrated in Fig. 2. Referring now to said figure, the control box 4 there illustrated includes switches 34, 35, 36, 37 and 38 adapted to control operation to the other glider as follows, right, up, left, down, and reset, respectively. Movement of arm 3 into any one of four given positions will operate one of the switches 34-37, and change the direction of flight of the glider and movement of arm 3 back to the central position will operate reset switch 38 and cause the glider to fly in a straight direction. Since it is desired that pulses should only be sent out when operative control is to be had of the glider there are positions of the arm 3 intermediate its central position, where it actuates reset switch 38, and the position in which it actuates one of the other switches 34-37, where none of the switches are actuated and no signal is transmitted.

While I have described one simple control box, it will be apparent that numerous types of control boxes may be provided which will function in the manner hereinabove indicated.

It will be seen that the aforescribed system has numerous safeguards against detection and interference. Transmission is in the form of separate pulses or discrete series of pulses. These pulses are modulated with two distinct frequencies, both of which must be determined in order to interfere with the receiver. The interference must have a relatively high amplitude because of the operation of the threshold device or lim-

iter 32, which prevents pulses of lesser amplitude from affecting the relays. Furthermore, the system permits of numerous changes to be made in order to prevent anyone from learning the combinations involved. The carrier frequency can be readily changed. Because of the width of the sub-carrier frequency band any of the five sub-carrier frequencies can be shifted over a relatively wide band. Likewise the sub-carrier frequencies may be shuffled about in relation to the particular operation which they control, either in the transmitter or in the receiver.

While I have described above the principles of my invention in connection with specific apparatus, it is to be clearly understood that this description is made only by way of example and not as a limitation on the scope of my invention. I claim:

1. In a remote control radio system, a transmitter comprising a single energy pulse generator, a first oscillator keyed by said pulse generator and adapted to generate oscillations at a selected one of a plurality of sub-carrier frequencies, a second oscillator keyed by said pulse generator and modulated by said first oscillator and adapted to generate carrier frequency oscillations; control means for substantially simultaneously actuating said pulse generator and selecting the sub-frequency of said first oscillator, and transmitter means for transmitting the output of said second oscillator; and a receiver comprising means for receiving and selecting pulses of said given carrier frequency and detecting them to remove the carrier frequency, means for directing said pulses to one of a number of channels in accordance with the pulse sub-carrier frequency, threshold means in said channels for blocking all energy having less than a given amplitude, and devices arranged in said channels adapted to be actuated by said pulses.

2. In a transmitter having a main carrier oscillator; oscillator means for producing any one of a plurality of predetermined sub-frequency signals as modulating energy for said main carrier oscillator, a single energy generator for simultaneously keying said main carrier oscillator and said oscillator means, and control means for said single energy generator and said oscillator means for selectively determining the sub-frequency output of said oscillator means during the operation of said single energy generator.

3. A transmitter comprising a single energy pulse generator, a first oscillator keyed by pulses from said generator and adapted to generate oscillations at a selected one of a plurality of sub-carrier frequencies, a second oscillator keyed by said single energy generator and modulated by said first oscillator and adapted to generate carrier frequency oscillations, control means for substantially simultaneously actuating said single energy generator and selecting the sub-frequency of said first oscillator, and means for transmitting the output of said second oscillator.

4. In a remote-control radio system, a transmitter comprising a source of carrier frequency, means for selectively generating a plurality of sub-carrier frequencies, means coupled to said source and said selective generating means for generating pulses to control operation of said source and said selective generating means, control means for controlling operation of said pulse generating means and for selecting a particular one of said sub-carrier frequencies, means for modulating energy from said source with said selected sub-carrier frequency; and a receiver

comprising means for receiving and selecting pulses of said given carrier frequency, means for detecting said last mentioned pulses to remove the carrier frequency, means for directing said pulses to one of a number of channels selected in accordance with the pulse sub-carrier frequency, and devices arranged in each of said channels adapted to be actuated by said pulses.

5. A transmitter comprising a source of carrier frequency, means for selectively generating a plurality of sub-carrier frequencies, means coupled to said source and said selective generating means for generating pulses to control operation of said source and said selective generating means, control means for controlling operation of said pulse generating means and for selecting a particular one of said sub-carrier frequencies, and means for modulating energy from said source with said selected sub-carrier frequency.

6. A radio remote-control system comprising a source of carrier frequency, means for selectively generating a plurality of sub-carrier frequencies, means coupled to said source and said selective generating means for generating pulses to control operation of said source and said selective generating means, control means for controlling operation of said pulse generating means and for selecting a particular one of said sub-carrier frequencies, means for modulating energy from said source with said selected sub-carrier frequency, means for receiving said modulated carrier frequency a plurality of translating means coupled to said receiving means, each

adapted to respond in accordance with the selected sub-carrier frequency.
